CLAIM

The ornamental design for a shoe, as shown and described.

DESCRIPTION

FIG. 1 is a photographic front perspective view of a shoe showing my new design;

FIG. 2 is a side view thereof;

FIG. 3 is an opposite side view thereof; and,

FIG. 4 is a rear view thereof.

The photographic area is claimed. The broken lines showing the remainder of the shoe represent unclaimed subject matter and form no part of the claimed design.
